UNITED STATES PATENT OFFICE

JERRY J. KOKESH, OF ST. LOUIS, MISSOURI.

ACETYLENE-GAS GENERATOR.

949,960.

Specification of Letters Patent. Patented Feb. 22, 1910.

Application filed February 16, 1907. Serial No. 357,689.

To all whom it may concern:

Be it known that I, JERRY J. KOKESH, a citizen of the United States, residing at St. Louis, in the State of Missouri, have invented new and useful Improvements in Acetylene-Gas Generators, of which the following is a specification.

My invention relates to acetylene gas generators, and it consists in the construction and arrangement of parts as will be herein-after described and particularly pointed out in the claim.

Referring to the drawings forming part of this specification and in which similar reference characters indicate like parts in both the views, Figure 1 represents an elevation of my improved generator; and Fig. 2 a vertical sectional view thereof.

The reference numerals 1 and 2 indicate the generators proper, 3 the floating bell and 4 the main water tank. Inside of the generators 1 and 2 are arranged the carbide holders 5 divided by means of partitions 6 into several compartments. This container 5 is open at the top and each compartment is provided with a series of holes or perforations 7 through its side, the perforations in each compartment being at a higher level than those in the next adjacent compartment.

Arranged above the generators 1 and 2 is the washing tank 8 from the top of which extends a pipe 10 opening into the bell 3 above the water level. From each generator extends an inverted U-shaped pipe 9 which enters the washing chamber 8.

Water is supplied to the carbide generators through pipes 16 and 17 which are united at their top to form a double funnel 15 and the lower end of the pipes 16 and 17 pass through water tight joints into chambers 18 and 19, which in turn are connected by pipes 20 and 21 with the generators. Arranged above the funnel 15 is an adjustable spout 14 leading from a pipe 12 which in turn connects with a water tank such as 11 placed at a suitable elevation. The pipe 12 is closed near the spout 14 by a valve 13, hereinafter referred to.

Water is supplied to the washing chamber 8 through a vertical pipe and funnel 24. To this pipe also is connected a discharge cock 25 whereby the water in the washing chamber may be allowed to run out.

Near the top of the bell 3 is attached a bracket 30 from which is suspended by

means of a chain a ball 26. This ball is adapted to coöperate with a cup 27 carried at one end of a lever 28 attached to the valve 13 and to the other end of which is hung a weight 29 to counterbalance the cup.

31 designates the main discharge pipe by means of which the gas is conducted from the bell to the points of consumption.

Located near the permanent water level 65 of the main tank is a safety valve 32. This consists of an inverted cup suspended by means of a chain 33 from the top of the bell, and normally resting over the open end of a waste pipe 34.

The operation of my improved generator is as follows: Water from the tank 11 is admitted by means of the spout 14 into the pipe 16 (say) and gradually fills the chamber 18 up to the water level 22 before flowing into the generator 1. It will be noted that this arrangement constitutes a water seal which will prevent the gas from flowing back through the pipe 16 and at the same time obviates the use of troublesome valves. From the chamber 18 the water flows through the pipe 20 little by little into the chamber 1 and gradually rises therein until it reaches the lower set of holes 7 in the container 5. It then enters that compartment of the container and attacks the contained carbide. The gas thus produced passes upward through pipe 9 and after being purified by washing in the water contained in the chamber, it escapes through pipe 10 into the bell 3. The washing chamber arrangement also has another advantage in that it acts as a water seal to prevent the gas from bell 3 flowing backward to the generator and thus escaping when the end of 95 the generator is removed for the purpose of recharging the same. In case the bell 3 tends to rise too high owing to excessive pressure, the safety valve 32 will be opened and the gas allowed to escape through pipe 100 34. In case the bell descends too low due to the fact that the gas is becoming exhausted, ball 26 drops into cup 27 and thereby turning the valve 13 permits a fresh supply of water to flow to the generating chambers. 105

As the water continues to rise in the generator 1 it successively reaches and pours through the orifices 7 in the various compartments progressively. When the carbide has been entirely used up from all the 110 compartments water continues to rise in the generator 1 until it completely fills the same.

and then backs up in the pipe 16 until the level indicated by the line 23 is reached. It then ~~flows~~ into pipe 17 and acts upon the carbia in the other generator 2 in a similar manner. While the generator 2 is in operation, generator 1 may be re-charged merely by swinging the spout 14 from the position shown in Fig. 1 to one that will bring its discharge end over the pipe 17.

It will thus be seen that I have provided an apparatus which is free from valves and which operates automatically to maintain a proper supply of gas in the bell at all times, and it is thought the numerous advantages of the device will be readily appreciated by those skilled in the art.

Having thus described my invention, I claim as new and desire to secure by Letters-Patent:

20 A structure of the character described comprising a main tank with a plurality of generators therein, pipes spaced apart and having a double funnel secured thereto at

their upper ends, a pipe arranged above the funnel and connected to a suitable water supply, chambers connected to said generators, said plurality of pipes being connected to the chambers and having their lower ends arranged above the bottoms thereof, the pipe above the funnel having a 25 valve therein, said valve being provided with a lever pivotally connected therewith, said lever having on one end a cup and on its other end a weight, and means adapted to contact with said cup, a spout pivotally connected to said valve to permit of the same being interchangeable from one of the funnel pipes to the other, substantially as specified.

In testimony whereof, I affix my signature 30 in presence of two witnesses.

JERRY J. KOKESH.
